INTERNAL COMBUSTION ENGINE

Carl T. Doman, Syracuse, N. Y., assignor to Doman & Marks, Syracuse, N. Y., a copartnership composed of Carl T. Doman and Edward S. Marks

Application July 7, 1933, Serial No. 679,389

6 Claims. (Cl. 123—195)

This invention relates to internal combustion engines, and has for its object, a cylinder construction whereby the barrel and head, or the barrel or head is formed of an aluminum alloy having an insert of steel or ferrous metal alloy having approximately the same coefficient of expansion as the aluminum alloy, as nickel steel. It further has for its object, a head construction for internal combustion engines wherein the heads are of a metal, as aluminum alloy, having a greater coefficient of expansion than the cast iron barrels of the cylinders, the heads having reinforcing inserts of nickel steel metal, so that the head can be bolted in the ordinary manner to the cast iron cylinder barrel, and be held tight against the barrels, or the gasket between them, without warping and separating from the end of the cylinder, or from the gasket, and hence avoiding leakage at the gasket surface, that is, preventing the formation of clearances between the cylinder head and the cylinder barrel.

It further has for its object, a cylinder head of an aluminum alloy where the head is shrunk on, or screwed on the barrel of the cylinder with an insert of nickel steel alloy for reinforcing and relieving the aluminum of the holding strains.

The invention consists in the novel features and in the combinations and constructions hereinafter set forth and claimed.

In describing this invention, reference is had to the accompanying drawings in which like characters designate corresponding parts in all the views.

Figure 1 is a fragmentary vertical sectional view of a cylinder in which the barrel and head are formed of aluminum, and each provided with a reinforcing insert of nickel steel alloy, the head being of a modified F type.

Figure 2 is a plan view of parts seen in Figure 1 showing a head common to a plurality, as a pair of cylinders.

Figure 3 is a view, similar to Figure 1, of cylinder head construction embodying my invention where the head is shrunk onto the barrel of the cylinder.

Figure 4 is a fragmentary view similar to Figure 3 showing the head as screwed onto the barrel of the cylinder.

Figure 5 is a view similar to Figure 1 showing the engine embodying this invention with the valve ports in the head.

Aluminum heads may be held in place by means of steel studs screwed into the cylinder, or cylinder block. As the aluminum head will expand at a considerably greater rate than the bolt or

stud holding it, the metal underlying the nut on the stud, or the washer underneath the nut, will be subjected to very high compressive stresses, and under high temperatures these stresses are liable to exceed the elastic limit of the aluminum, or aluminum alloy. This results in permanent setting and hence in looseness of the aluminum head when the engine cools, and clearances or leaks between the head and the cylinder, or between the head and the gasket, or between the gasket and the cylinder.

The principal object of this invention is to reinforce the head, or the portion thereof nearest the cylinder, with an insert of a metal having about the same coefficient of expansion as the aluminum alloy, as an alloy of nickel and steel, or nickel and cast iron.

The invention is adapted for water cooled, or air cooled engines, and I have shown it as embodied in air cooled engines, as it is especially useful in air cooled engines.

In Figures 1 and 2, 1 designates an aluminum alloy head and 2 the barrel of the cylinder, and the latter, in an air cooled engine, is provided with heat radiating flanges as 3, and in a water cooled engine with a water jacket. The head may also be provided either with heat radiating flanges, or a water jacket.

4 designates an insert of a metal, as an alloy of nickel and ferrous metal, having about the same coefficient of expansion as aluminum alloy, this being located or embedded in the head in the portion thereof which abuts against the end of the barrel of the cylinder. In case of a single cylinder, this insert would be annular in general form, and in case of a multi-cylinder, as shown in Figure 2, would be of the outline of the margin of a head common to a plurality of cylinders. The insert may be provided with bosses 5 at suitable intervals and formed with holes 6 for receiving the studs 7 projecting upwardly from the cylinder, or the cylinder block, on the upper end of which studs nuts 8 are screwed to secure the head to the cylinder, or the cylinder block. Owing to the insert, which is rigid, the aluminum head

does not lose its strength when subjected to the temperatures of the combustion chamber and hence, leakage at the gasket 9 between the head and the cylinder, or the cylinder block, is prevented and thus, one of the disadvantages of the use of an aluminum head is avoided. As here shown, the insert is channel shaped in cross section or a cross section taken through any part thereof consists of an intermediate upright web and opposing side flanges. The cylinder, illus-

trated in Figures 1 to 4, is of the outside valve type, that is, an F head, although the type of head is of no consequence, insofar as my insert is concerned, except that the insert is 5 formed with loops 25 or offsets around the valve ports so that the continuity of the insert is not broken. By F head is meant a head structure in 10 which the valves are located in a lateral offset as in an L head engine, but with one valve in 15 the bottom and the other in the top of the offset.

In Figure 1, the barrel of the cylinder is also formed of an aluminum alloy with an insert 10 of a nickel ferrous metal alloy having approximately the same coefficient of expansion as the 15 aluminum alloy, this being embedded in the aluminum alloy but arranged to form a liner for the barrel on which liner the piston works.

In Figure 3, a head 11 is shown which is shrunk on the cylinder 12, and the head reinforced by 20 an annular insert 13 in the portion thereof which surrounds the upper margin of the barrel of the cylinder.

In Figure 4, the head 21 is shown as screwed on the cylinder 22, and the insert 23 located or 25 embedded in the threaded margin of the head.

In Figure 5, the cylinder head is formed with 30 valve seats and ports 26, 27 in line with the barrel, that is, they are located in the circle of the head end of the barrel instead of being offset 35 or outside of the circle as in Figure 1.

In forming the head and the barrel with the 35 inserts, the aluminum alloy is cast around the inserts, and the inserts, being of the same coefficient of expansion as the aluminum alloy, rigidly unite with the head and do not develop looseness.

What I claim is:

1. In an engine construction, a cylinder, an 40 aluminum alloy head having a reinforcing insert in the margin thereof which is adjacent the barrel, said insert extending entirely around the margin of the head and embedded within the same and being of a metal having approximately the same coefficient of expansion as the aluminum 45 alloy.

2. In an engine construction, a cylinder, an 50 aluminum alloy head having an insert in the portion thereof which is adjacent the barrel of the cylinder, said insert extending entirely around the margin of the head and embedded within the

same and being nickel ferrous metal alloy having approximately the same coefficient of expansion as the aluminum alloy.

3. In an engine construction, a cylinder, a detachable head of aluminum alloy for the cylinder, the head being opposed to the upper edge of the cylinder with a gasket between the opposing edges, the head having an insert of nickel ferrous metal alloy having approximately the same coefficient of expansion as the aluminum alloy, said 5 insert extending entirely around the margin of the head and embedded within the same and being located in the portion of the head which is adjacent the cylinder, and being provided with 10 bosses for studs extending upwardly from the cylinder barrel and forming part of the means for securing the head to the cylinder barrel.

4. In an engine construction, a cylinder, an aluminum alloy head having its margin enclosing and snugly fitting the upper margin of the 20 barrel of the cylinder, and an insert extending entirely around the margin of the head and embedded within the same and being of nickel ferrous metal alloy, having approximately the same coefficient of expansion as the aluminum alloy, 25 located in the portion of the head enclosing the margin of the cylinder barrel.

5. In an internal combustion engine construction, a head part and a barrel part, one of said 30 parts being formed of an aluminum alloy and having a reinforcing insert therein, said insert extending circumferentially throughout the entire margin of the part in which it is embedded and being of a nickel steel alloy having approximately the same coefficient of expansion as the aluminum 35 alloy.

6. In an internal combustion engine construction, an aluminum alloy barrel, and an aluminum 40 alloy head secured to the barrel, the barrel having an insert embedded therein and forming a liner of a nickel steel alloy having approximately the same coefficient of expansion as the aluminum alloy, and the head having a reinforcing insert in the portion thereof adjacent the barrel, which 45 insert extends entirely around the margin of the head and embedded within the same and is of a nickel steel alloy having approximately the same coefficient of expansion as the aluminum alloy.

CARL T. DOMAN. 50
